[57] CLAIM

The ornamental design for a snow and ice removal device, as shown and described.

DESCRIPTION

FIG. 1 is a right rear perspective view of a snow and ice removal device, showing my new design;

FIG. 2 is a right side elevational view thereof;

FIG. 3 is a left side elevational view thereof;

FIG. 4 is a top plan view thereof;

FIG. 5 is a reduced right side elevational view thereof, shown in an alternate position, the broken line showing the railroad tracks is for illustrative purposes only, and forms no part of the claimed design;

FIG. 6 is a reduced right side elevational view thereof, in position to remove the snow and ice; and,

FIG. 7 is a front elevational view thereof.
